(57) **CLAIM**

The ornamental design for a command and control panel of electric circuit breaker as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the command and control panel of electric circuit breaker of the first embodiment showing my new design;

FIG. 2 is a front view thereof;

FIG. 3 is a right side view thereof;

FIG. 4 is a left side view thereof;

FIG. 5 is a top plan view thereof;

FIG. 6 is a bottom plan view thereof;

FIG. 7 is a front view thereof shown within an environment;

FIG. 8 is a perspective view of the command and control panel of electric circuit breaker of the second embodiment;

FIG. 9 is a front view thereof;

FIG. 10 is a right side view thereof;

FIG. 11 is a left side view thereof;

FIG. 12 is a top plan view thereof;

FIG. 13 is a bottom plan view thereof;

FIG. 14 is a rear view thereof;

FIG. 15 is a perspective view of the command and control panel of electric circuit breaker of the third embodiment;

FIG. 16 is a front view thereof;

FIG. 17 is a right side view thereof;

FIG. 18 is a left side view thereof;

FIG. 19 is a top plan view thereof;

FIG. 20 is a bottom plan view thereof;

FIG. 21 is a rear view thereof;

FIG. 22 is a perspective view of the command and control panel of electric circuit breaker of the fourth embodiment;

FIG. 23 is a front view thereof;

FIG. 24 is a right side view thereof;

FIG. 25 is a left side view thereof;

FIG. 26 is a top plan view thereof;

(Continued)

FIG. 27 is a bottom plan view thereof;
 FIG. 28 is a rear view thereof;
 FIG. 29 is a perspective view of the command and control panel of electric circuit breaker of the fifth embodiment;
 FIG. 30 is a front view thereof;
 FIG. 31 is a right side view thereof;
 FIG. 32 is a left side view thereof;
 FIG. 33 is a top plan view thereof;
 FIG. 34 is a bottom plan view thereof;
 FIG. 35 is a perspective view of the command and control panel of electric circuit breaker of the sixth embodiment;
 FIG. 36 is a front view thereof;
 FIG. 37 is a right side view thereof;
 FIG. 38 is a left side view thereof;
 FIG. 39 is a top plan view thereof;
 FIG. 40 is a bottom plan view thereof;
 FIG. 41 is a perspective view of the command and control panel of electric circuit breaker of the seventh embodiment;
 FIG. 42 is a front view thereof;
 FIG. 43 is a right side view thereof;
 FIG. 44 is a left side view thereof;
 FIG. 45 is a top plan view thereof;
 FIG. 46 is a bottom plan view thereof;
 FIG. 47 is a perspective view of the command and control panel of electric circuit breaker of the eighth embodiment;
 FIG. 48 is a front view thereof;
 FIG. 49 is a right side view thereof;
 FIG. 50 is a left side view thereof;
 FIG. 51 is a top plan view thereof;
 FIG. 52 is a bottom plan view thereof;
 FIG. 53 is a front view thereof shown within an environment;
 FIG. 54 is a perspective view of the command and control panel of electric circuit breaker of the ninth embodiment;
 FIG. 55 is a front view thereof;
 FIG. 56 is a right side view thereof;
 FIG. 57 is a left side view thereof;
 FIG. 58 is a top plan view thereof;
 FIG. 59 is a bottom plan view thereof; and,
 FIG. 60 is a rear view thereof.

The broken lines shown illustrate portions of the command and control panel of electric circuit breaker that form no part of the claimed design.
